(57) **CLAIM**

The ornamental design for a camera as shown and described.

DESCRIPTION

FIG. 1 is a front, top, and left perspective view of a camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is a front, top, and left side perspective view thereof, shown with the camera in condition of use.

The broken lines shown in the drawings represent portions of the camera that form no part of the claimed design.
